FRONT FORK FOR A BICYCLE

Charles F. Voytech, 208 S. La Salle St.,
Chicago, Ill. 60604.

Filed Apr. 12, 1967, Ser. No. 6,659

Term of patent 14 years

(Cl. D90—9)

FIG. 1

FIG. 2

FIG. 3

FIG. 4

FIG. 1 is a side elevational view of a front fork for a bicycle;

FIG. 2 is a plan view of the front fork for a bicycle of FIG. 1;

FIG. 3 is a bottom view of the front fork for a bicycle of FIG. 1; and

FIG. 4 is a front elevational view of the front fork for a bicycle of FIG. 1 looking toward the right in FIG. 1.

The broken lines on the figures are disclosed for illustration purposes only to show how the fork is used in the bicycle.

I claim:

The ornamental design for a front fork for a bicycle, substantially as shown and described.
